UNITED STATES PATENT OFFICE

AUSTIN A. WOOD AND EDWARD BOSS, OF COLUMBUS, OHIO

DESIGN FOR A SIGN

Application filed December 12, 1931. Serial No. 42,065. Term of patent 7 years.

To all whom it may concern:

Be it known that we, AUSTIN A. Wood and EDWARD Boss, citizens of the United States, residing at Columbus, in the county of Franklin and State of Ohio, have invented a new, original, and ornamental Design for a Sign, of which the following is a specification, reference being had to the accompanying drawing, forming a part thereof.

We claim:

The ornamental design for a sign, as shown.

AUSTIN A. WOOD.
EDWARD BOSS.
